United States Patent Office.

MARTIN GAYHART, OF YOUNG AMERICA, WISCONSIN.

Letters Patent No. 79,064, dated June 23, 1868.

IMPROVEMENT IN TRACE-BUCKLE.

The Schedule referred to in these Letters Patent and making part of the same.

TO ALL WHOM IT MAY CONCERN:

Be it known that I, MARTIN GAYHART, of Young America, in the county of Washington, and State of Wisconsin, have invented a new and useful Improvement in Trace-Buckles; and I do hereby declare that the following is a full, clear, and exact description thereof, which will enable others skilled in the art to make and use the same, reference being had to the accompanying drawings, forming part of this specification, in which—

Figure 1 is a plan view of my invention.

Figure 2 is a section of the same through the line $z z$ of fig. 1.

Similar letters of reference indicate like parts.

The object of this invention is to provide a buckle for leather traces or tugs, which shall be simple, effective, and easily operated.

It consists of two parts, which are pivoted together by the rod a , and which pinch the trace when strain is brought upon the two parts, whereby the pinching action relieves the tongue from a portion of the draught-strain of the trace, as will hereinafter be more fully set forth.

In the accompanying plate of drawings, the parts are shown at A A A' A'' and B B B' B'', and are pivoted together by the rod a , as shown.

The part A is formed with a corrugated cross-piece, A', bearing a tongue, e , which latter passes through a hole in the trace C, as shown.

The strap which connects the buckle to the harness is affixed to the cross-piece A'', whereby the draught-strain actuates the corrugated surface d of the cross-piece A', to pinch the trace between the cross-piece A' and the cross-piece B', which latter is also corrugated, as shown at b . The cross-piece B' also serves to sustain the end of the tongue e against the draught strain.

Lugs c , forming part of the part B B B', &c., serve to sustain a part of the draught strain, and thus relieve the rod a .

The part A is formed to fit against the said lugs at this point for that purpose.

Having thus described my invention, I claim as new, and desire to secure by Letters Patent—

The parts A A A' A'' and B B B' B'', pivoted together by a rod, a , and provided with a rigid tongue, e , corrugated cross-piece A' and B', all constructed and operating substantially as shown and described, and for the purpose set forth.
